UNITED STATES PATENT OFFICE.

FRANK L. YOUNG, OF WINDSOR, CONNECTICUT, ASSIGNEE, BY MESNE ASSIGNMENTS,
TO GOODELL-PRATT COMPANY, A CORPORATION OF MASSACHUSETTS.

DRILL.

Application filed September 7, 1923. Serial No. 661,384.

To all whom it may concern:

Be it known that I, FRANK L. YOUNG, a citizen of the United States, and resident of Windsor, in the county of Hartford and State of Connecticut, have invented certain new and useful Improvements in Drills, of which the following is a specification.

This invention is an improved portable motor-driven drilling machine of the general type in which a single portable casing encloses the rotary motor and bearings for the drill spindle, and conceals the power-transmitting connections between said motor and spindle.

One object of the present invention is to so construct the parts that the drill may be employed for drilling holes in one wall close to and parallel with the line of intersection of two other walls at right angles to each other and to the first mentioned wall, as for instance vertically into a floor close to the corner of a room. In my improved construction the only part limiting the distance from the corner of the room at which the drill may be placed, is the drill-carrying chuck itself.

A further object of my invention is to provide a simpler and more conveniently located means for controlling the application of motive fluid to the motor. If the motor be an electric one, such controlling means is in the form of a switch which may be operated by a button or other operating member directly on the handle, the said switch having its parts thoroughly and effectively protected, but at the same time readily accessible for cleaning, inspection or repair.

A further object of my invention is to provide a spirit level so positioned that the holding of the drill in a horizontal position is facilitated. The spirit level is positioned in the cover or casing for the switch so that it is readily removable from the drill casing in case it is necessary to readjust or replace it.

Other important features will be pointed out hereinafter, or will be apparent from a consideration of the drawings and description of a preferred embodiment.

In the accompanying drawings:

Fig. 1 is a side elevation of my improved construction.

Fig. 2 is another side elevation taken at right angles to the plane of Fig. 1.

Fig. 3 is a top plan view.

Fig. 4 is a vertical section on the line 4—4 of Fig. 2 on a larger scale and showing the parts of the switch and spirit level.

Fig. 5 is a face view of the switch parts, the cover being removed.

Fig. 6 is a transverse section on the line 6—6 of Fig. 4, and

Fig. 7 is a transverse section on the line 7—7 of Fig. 1, but on a larger scale.

In the accompanying drawings I have not illustrated the details of construction of the motor for driving the drill spindle. This motor may be of any suitable rotary type. So far as certain features of my invention are concerned this rotary motor may be operated by compressed air, steam or other motive fluid, but so far as other features of the invention are concerned, the motor is necessarily an electric motor. The rotary motor, irrespec-

tive of its character, is mounted in a cylindrical casing 10 having removable top and bottom end walls 11 and 12. The top wall or cover plate 11 is preferably formed integral with a handle 13 of what may be called the spade handle type, that is, it provides a hand grip portion 14 approximately parallel to the plane of the main cover plate and having each end rigidly connected thereto by arm portions 15 and 16. The bottom wall or plate 12 constitutes a casing for the transmission gearing from the main shaft 17 of the motor to the spindle 18 of the drill, and includes a bearing sleeve 19 for said spindle. This bearing sleeve is of approximately the same diameter as the drill 20. The spindle bearing sleeve 19 is parallel with but eccentrically disposed in respect to the body portion of the casing. As one important feature of my invention the extent of the eccentricity is such that the sleeve projects out beyond the periphery of the casing and the two lines of tangency A—B and B—C indicated in Fig. 7 intersect at an angle not materially greater than a right angle. By making the eccentricity 30 such that these two common tangents intersect at a right angle, the tool may be placed in the corner of a room with the line A—B representing one wall and the line B—C representing another wall at right angles thereto. When in this position the drill chuck will have its outer surface almost but not quite touching said walls, so that the drill may be freely rotated and a hole drilled at a distance from the walls which is only 40

very slightly greater than the radius of the drill chuck. The bottom plate 12 has a projecting rib portion 21 with its outer surface in alignment with the portion of the outer surface of the sleeve 19 which is outside of the circle of the body portion of the end plate, and the cover plate 11 has its arm portion or support 16 for the hand grip also extending out beyond the circle of the main portion of the cover plate so as to include a projection 22, the outer surface of which is in alignment with the outer surface of the sleeve 19 and the projecting flange 21. Thus the drill may be held parallel to the vertical walls adjacent to which the hole is to be drilled, by the contact with said walls of parts of both the plates 11 and 12 which are at opposite ends of the main casing.

As one important feature of my invention I mount the switch for controlling the motor on the outer surface of the main casing 10 between the projecting portions 21 and 22, and so design the switch that no part thereof projects radially beyond the outer surface of these projecting parts. The switch as shown includes an insulation block 23 secured to the surface of the drill casing 10 in any suitable manner as for instance by a couple of screws. Secured to the opposite side of this insulation block are the two switch contacts 24, each of which is connected to its corresponding wire 25 in the circuit of the motor. The wires preferably pass through the wall of the casing 10 closely adjacent to the switch contacts, so that very little of these wires is exposed. The movable member of the switch includes a plunger having a head 26 of insulation material and a conducting collar 27 at one end which, when the head is moved endwise, engages with the two switch contacts 24. The head is carried by a plunger 28 which is endwise movable in the supporting arm 16 of the handle. The plunger has a coil spring 29 normally tending to move it upwardly to break the electric circuit. The spring operates between the collar 30 on the plunger member, and a stop 31 screwed into the lower face of the projection 22. The hand grip portion 14 of the handle has a passage 32 therein which intersects the passage acting as a guide for the plunger member 28. These two passages are at approximately right angles although slightly at an obtuse angle. Within the passage 32 is a slide 33 which has a pointed end or cam part 34 which may ride over the upper end 35 of the plunger and force the latter downwardly. When the slide 33 is moved to the limiting position the end 35 of the plunger comes beyond the cam portion 34 and the parts will automatically remain in position. The outer end of the passage 32 may be closed by a small screw plug 36. Any suitable means may be employed for operating the

slide 33. As shown there is provided a button 37 which has a threaded spindle rigidly securing it to the slide 33 and movable back and forth in a slot 38 in the upper side of the hand grip portion 14 of the handle. This button thus comes closely adjacent to the normal thumb position of an operator grasping the handle 13, and thus by moving the button back and forth the switch may be opened and closed. By reason of the cam ends 34 and 35 it will be noted that the slide 33 will be forced back the instant it is moved back to a short distance so that there will be a quick break of the circuit at the contacts 24 and 27.

The position of the switch is important not only because of the possibilities which it affords for simple operating mechanism and for the protecting of the switch parts behind the contour of the projections 21 and 22, but also because of the facilities which are offered for the attachment of a simple cover member. This cover member is shown as of approximately crescent shape in cross section with the inner surface curved to follow the contour of the cylindrical casing 10 and the outer surface curved to conform to the outer surface of the projections 21 and 22. The cover member has a chamber or cavity 41 opening rearwardly at the upper portion so as to receive and enclose the switch parts. The cover member may be secured in place in any suitable manner as for instance by screws 42 extending through the marginal portion into the casing 10. Below this switch-receiving chamber the body of the cover is provided with a vertically disposed opening 43 within which is mounted the bulb or tube 44 of a spirit level. This is properly positioned in respect to an opening or window 45 in the wall of the cover and is sealed and held in position by any suitable self-hardening composition 46 such as plaster of Paris, which, together with the tube 44, completely fills the passage 43. It will be noted that in case the tube 44 breaks or leaks or is found to be not properly positioned in respect to the axis of the drill, it is not necessary to send the whole drill back to the factory for repair, as the cover 40 is the only part carrying this spirit level. The cover being easily removable permits the parts of the switch to be quickly and easily inspected or adjusted, and the removal of the cover does not disturb any of the electrical connections. The cover serves not only to protect and conceal the switch parts, but also to carry the spirit level and to form a continuation of the projections 21 and 22 and give the drill a smooth, continuous, vertical surface.

Even though the switch is on the same side of the casing as the drill spindle it is preferable that the electric wire connection to the drill be upon the opposite side so as

to not interfere with the drilling closely adjacent to a corner. As shown a bracket 46 is secured to the casing 10 opposite to the cover 40 and to this bracket is secured a supplementary handle 47 in the form of a horizontal rod or tube, and a clutch member 48 for receiving and retaining the end of the cable 49. Thus the cable and the handle 47 are diametrically opposite to the position of the drill so as to not in any way interfere with the positioning of the latter.

Having thus described my invention, what I claim as new and desire to secure by Letters Patent is:

15 1. A power driven drill including a cylindrical casing for the prime mover, said casing being provided at one end with a spindle bearing sleeve eccentric in respect to the casing and of smaller diameter, a portion of said sleeve extending beyond the periphery of the casing, a drill spindle, and a drill chuck of approximately the diameter of the sleeve, the two planes tangent to the casing and sleeve intersecting at approximately a right angle.

20 2. A power drill including a cylindrical motor casing having projections adjacent to the opposite ends and presenting curved surfaces having straight line elements in alignment, and parallel with the axis of the casing, the two planes tangent to the casing and the projections intersecting at approximately a right angle.

25 3. A power driven drill including a cylindrical casing for the prime mover, a pair of projections presenting cylindric surfaces in alignment with each other lengthwise of the casing, the common axis of said cylindric surfaces being parallel to the axis of the casing, the two planes tangent to the casing and projections intersecting at approximately a right angle.

40 4. A power driven drill including a cylindrical casing for the prime mover, a pair of projections presenting cylindric surfaces in alignment with each other lengthwise of the casing, the common axis of said cylindric surfaces being parallel to the axis of the casing, the two planes tangent to the casing and projections intersecting at approximately a right angle, and a drill chuck coaxial with said projections and having its spindle rotatably mounted in one of them.

45 5. A power driven drill including a cylindrical casing for the prime mover, said casing having laterally projecting portions adjacent to opposite ends thereof, the two planes tangent to said casing, and said projecting portions intersecting at approximately a right angle, means on the exterior of the casing between said projections for controlling the prime mover and a cover protecting said controlling means and within the angle between said planes.

60 6. A power driven drill including a cylind-

rical motor casing having top and bottom plates provided with aligned laterally extending projections for engaging with a wall to guide the drill parallel to said wall, and a controlling switch between said projections. 70

7. A power driven drill including a cylindrical motor casing having top and bottom plates provided with aligned laterally extending projections for engaging with a wall to guide the drill parallel to said wall, a handle rigid with one of said plates, a controlling switch between said projections, and means carried by said handle for operating said switch.

8. A power driven drill including a cylindrical motor casing having top and bottom plates provided with aligned laterally extending projections for engaging with a wall to guide the drill parallel to said wall, a controlling switch between said projections, and a cover plate for said switch having its outer surface substantially following the contour of said projecting portions.

9. A power driven drill including a cylindrical motor casing, a switch mounted upon the exterior of said casing, a handle rigidly secured to the top of said casing, a switch-operating rod carried by said handle outside of the periphery of the casing, and movable in the general direction of the length of the casing for operating said switch, and a slide on said handle, movable at an angle to said operating rod for controlling the latter.

10. A power driven drill including a motor casing, a controlling switch upon the exterior thereof, a top plate having a handle rigid therewith, and including a portion disposed radially beyond the periphery of the body of the casing, and a longitudinally movable rod mounted in said projecting portion for operating the switch. 100

11. A power driven drill including a cylindrical motor casing, top and bottom end plates having aligned portions projecting radially beyond the periphery of the body of the casing for engaging with a wall to guide the drill parallel to said wall, the projecting portion of one plate forming a portion of the spindle bearing and the projecting portion of the other plate having a switch operating member, a switch mounted on the outer surface of the casing between said projecting portions, and a cover plate for said switch having its outer surface conforming in contour to said projecting portions for controlling the latter. 110

12. A power driven drill including a cylindrical motor casing, top and bottom end plates having aligned radially projecting portions, a switch mounted on the exterior of the casing between said projecting portions, and a cover plate for said switch also mounted between and protected by said projecting portions. 125

13. A power driven drill including a motor casing having radially projecting portions adjacent to opposite ends thereof and having cylindric surfaces in alignment with each other lengthwise of the casing, the aligned axes of said projections being parallel to the axis of the casing and a member secured to said casing between said projecting portions and removable therefrom, said member having a spirit level carried thereby.

14. A power driven drill including a motor casing having a switch mounted upon the exterior of the peripheral wall thereof, a cover plate having a handle including a

hand grip portion and end portions connecting the latter with the cover plate, one of said end portions projecting radially beyond the periphery of the motor casing, a switch operating rod movable endwise in said last mentioned end portion, a slide movable endwise in said hand grip portion for moving said operating rod, and a button on the upper surface of the hand grip portion and connected to said slide.

Signed at East Hartford, in the county of Hartford and State of Connecticut, this 25th day of May, A. D. 1923.

FRANK L. YOUNG.
